CASING WITH RESERVOIR AND HAND ACTUATED DISCHARGE VALVE

Norman S. Gilbert, Brooklyn, N. Y.

Application June 19, 1947, Serial No. 755,693

8 Claims. (Cl. 15—97)

1

This invention relates to hand actuated disc polishing machines such as commonly used in polishing surfaces of any type or kind. Still more particularly, the invention deals with a machine which can be used as a hand polishing machine, that is to say, where the machine can be conveniently and easily guided by hand over a surface being polished, the machine having a pair of hand grip portions with a control switch accessible to a finger of one hand and a fluid release plunger accessible to the finger of another hand when both hands are engaging the hand grip portions of the machine.

The novel features of the invention will be best understood from the following description when taken together with the accompanying drawings in which certain embodiments of the invention are disclosed, and in which the separate parts are designated by suitable reference characters in each of the views, and in which:

Fig. 1 is a side view of the hand grip and cylinder side of a machine made according to my invention, with part of the construction broken away and in section.

Fig. 2 is a plan view of the structure as seen in Fig. 1.

Fig. 3 is an enlarged sectional view on the line 3—3 of Fig. 2, omitting the polishing pad.

Fig. 4 is a section on the broken line 4—4 of Fig. 3; and

Fig. 5 is a partial section on the line 5—5 of Fig. 3.

It is the purpose of my invention to provide a simple and economical lightweight constructed polishing machine which can be conveniently operated by hand in movement of the machine over a surface being polished, thus adapting the machine for polishing or buffing surfaces of any type or kind.

Considering Fig. 3 of the drawing, it will be seen that the machine comprises a main casting or casing 10 in one large diameter cylinder 11 of which is supported an electric motor 12. At the other side of the casing is a smaller diameter cylinder 13 for support of the polishing fluid or other material 14, used in the operation of the machine. The two cylinders 11 and 13 are joined in a connecting bridge or web portion 15, note Fig. 4, having a vertical bore or passage 16 in which is disposed a vertically movable plunger valve 17, the operation of which is later described.

Arranged upon the top of the cylinder side 11 of the casing is a dome-shaped cap 18 facilitating insertion and removal of the motor, and this cap includes two integral and oppositely extend-

2

ing L-shaped hand grip portions 19 and 20, note Figs. 1 and 2. The cap has two opposed recess portions 21—22 receiving the heads of bolts 23—24, which secure the cap in place and engage threaded portions of the casing, as at 25—26.

The cap 18 has a ball bearing mounting 27 for one end of the motor shaft 28 and the other end 29 of the motor shaft passes through a similar bearing 30 in the lower portion of the casing 10, as clearly seen in Fig. 3. Secured to the end 29 of the motor shaft is a drive pinion 31 which for the major part is disposed outwardly of the casing 10. Supported in the casing 10 is a baffle 32 and another baffle 33 is supported on the shaft 29 adjacent a collar 34, and these baffles are to prevent any possible lubricant from entering the motor chamber of the casing.

Intermediate the cylinder portions 11—13, the lower portion of the casing has a recess as at 35, note Fig. 3, in which is arranged a fluid discharge nozzle 36 having an enlarged flange portion 37 fitting in the recess 35 and secured to the casing as by screws 38. The nozzle 36 has a reduced discharge opening 39 and inwardly of the discharge end of the nozzle is a circumferential groove 40. The nozzle forms a center axis or stud for rotation of the pad supporting and driving disc 41. The disc 41 has an upturned and inwardly extending peripheral flange 42 forming means for retaining the polishing pad or other polish member 43 in position. The pad or member 43 simply comprises a circular piece of heavy lamb's wool or other soft material having means at the edge for tying or otherwise securing the same around the flange portion so that the pad member 43 becomes securely fixed to the disc. The central portion of the pad or member 43 is apertured to register with the discharge 39 of the nozzle so that the fluid 14 can pass substantially directly onto the surface being polished.

To reinforce and strengthen the disc 41, I employ a heavy disc-like frame 44 of less diameter than the disc 41 to form an annular recess or chamber 45 inwardly of the flange 42 into which the peripheral edge of the member 43 can extend. The frame 44 has a central hub portion 46 between which and the nozzle stud 36 is disposed a double ball bearing 47 providing free rotation of the disc. Secured to and keyed to the peripheral portion of the frame 44, as seen at 48, is an internal gear 49, the diameter of which is such as to register with the pinion 31 on the motor shaft, as clearly seen at the left of Fig. 3 of the drawing. This provides the drive for the disc, as will be apparent.

The fluid cylinder 13 communicates with the bore 16 through a passage 50 which opens into an enlarged portion or side extension of the bore 16, as seen at 51, at a point above where the bore 16 opens into the upper enlarged chamber 52 of the stud nozzle 36, as clearly seen in Fig. 3 of the drawing. It will thus be seen that as the plunger valve 17 is raised, the fluid 14 is permitted to enter the chamber 52 and be discharged through the nozzle discharge 39.

The plunger valve has a transverse aperture 53 having a semi-circular enlargement 54 at one side thereof and the web 15 has an aperture 55 registering with the plunger aperture, in which is mounted an operating arm 56, which extends into the aperture 53 of the plunger valve 17 and is adapted to raise said valve against the action of a spring 57, seating on the upper end of the valve. The upper end of the spring is housed in a bore 58 formed in the cap 18, as seen in Fig. 3.

The hand grip portions 19 and 20 are of channel cross sectional form in order to lighten the same, and in the channel of the hand grip 19, adjacent the bore 58, is a long bearing portion 59 in which is mounted a manually operated plunger 60 having an enlarged fingerpiece head 61. To the lower end of the plunger is pivoted the arm 56, as seen at 62. It will thus be seen that the spring 57 normally supports the plunger in raised position with the valve 17 in closed position. By depressing upon the fingerpiece 61, the plunger rod 60 is moved downwardly and the valve 17 is moved upwardly against the action of the spring 57. In this operation the arm 56 has a free pivotal action in the aperture 55.

Arranged in the fluid cylinder 13 is a piston 63 which is held in pressure engagement with the fluid 14 through the medium of a spring 64 seating on the piston and on a detachable cap 65, having any suitable quick detachment with the upper open end of the cylinder 13, for example, by pins 66 engaging bayonet slots 67 in the cylinder 13. The cap 65 has a center depending lug 68 apertured to receive one end of a chain or other flexible coupling 69, the other end of which is secured centrally of the piston 63, as seen at 70, in Fig. 3 of the drawing. The cap 65 has a radially and upwardly extending fingerpiece portion 71 facilitating attachment and detachment thereof.

Upon removing the cap 65, the piston 63 may be drawn upwardly through the chain 69 in the operation of refilling the cylinder 13 with fluid, as at 14. The spring 64 will be tensioned to discharge substantially all of the fluid cylinder 13 and in normally filling or replenishing the supply of fluid to the cylinder it is desirable to not fill the cylinder 13 more than approximately half full.

It will be apparent from a consideration of Figs. 2 and 3, that the hand grip portions 19 and 20 are disposed centrally and extend radially with respect to the axis of rotation of the disc 41 upon the nozzle stud 36. Considering Fig. 1 of the drawing, it will be apparent that the lower portion of the casing 10 terminates in a disc-like portion 72, the upper edges of which are preferably rounded, as seen in said figure, and the cylinder portion 11 is offset outwardly with respect to this disc, whereas the cylinder 13 is disposed within the peripheral boundaries of the disc.

Secured to the hand grip portion 20 in substantially the same position as assumed by the manual control plunger 60 is a standard electric

switch 73 with which connects the electric extension cord 74 for providing source of current supply to the motor of the machine. Extending from the switch are conductor wires 75 which extend into the cap 18 for coupling with the motor 12, as will be apparent. This construction is indicated in Fig. 2 of the drawing, but the details thereof are omitted from the other figures, as this wiring forms no part of the present invention.

One distinctive feature of my invention, however, resides in the fact that the two controls, namely the button 61 and the switch 73 are disposed on inner portions of the hand grips 19 and 20 so that in grasping these hand grips, the thumbs of the hands can be utilized to control stopping and starting of the motor and discharge of polishing or other fluid 14 through the nozzle discharge 39 directly onto the surface being polished. One advantage of this particular construction resides in the fact that a definite control of the amount of polishing or other fluid supplied to the surface is maintained. This obviates undue saturation of the polishing medium or member 43, maintaining the same in at least a semi-dry state at all times.

While the machine has been shown and described as a polishing machine, it will be apparent that any type of facing material can be mounted upon the disc 41 or attached to the frame 44. The assemblage comprising the frame 44, disc 41 and the bearing 47 is made detachable with respect to the rest of the machine or the nozzle stud 36 through the medium of a lock spring ring 76 engaging the annular recess 40, as clearly seen in Fig. 3 of the drawing.

Considering Fig. 3 of the drawing, it will appear that the lower end of the cylinder 13 has a shoulder portion 77 eliminating downward movement of the piston 63, so as to avoid sticking of the piston in the cylinder, as will be apparent.

Having fully described my invention, what I claim as new and desire to secure by Letters Patent is:

1. In a machine of the class described, a casing having two cylinders joined by a connecting web, one of said cylinders being adapted to contain an electric motor vertically disposed in said cylinder, the other cylinder forming a fluid reservoir, said web containing a valve bore, a plunger valve mounted in said bore and controlling discharge from said reservoir, a pair of hand grips on the casing centrally thereof, and manually actuated means on one of said hand grips for moving the plunger valve into open position in controlling discharge of fluid from said reservoir.

2. In a machine of the class described, a casing having two cylinders joined by a connecting web, one of said cylinders being adapted to contain an electric motor vertically disposed in said cylinder, the other cylinder forming a fluid reservoir, said web containing a valve bore, a plunger valve mounted in said bore and controlling discharge from said reservoir, a pair of hand grips on the casing centrally thereof, manually actuated means on one of said hand grips for moving the plunger valve into open position in controlling discharge of fluid from said reservoir, and a spring in said bore and engaging said plunger valve to normally support the valve in closed position.

3. In a machine of the class described, a casing having two cylinders joined by a connecting

web, one of said cylinders being adapted to contain an electric motor vertically disposed in said cylinder, the other cylinder forming a fluid reservoir, said web containing a valve bore, a plunger valve mounted in said bore and controlling discharge from said reservoir, a pair of hand grips on the casing centrally thereof, manually actuated means on one of said hand grips for moving the plunger valve into open position in controlling discharge of fluid from said reservoir, and said hand grips constituting part of a cover forming a closure for said first named cylinder.

4. In a machine of the class described, a casing having two cylinders joined by a connecting web, said web having a bore, the upper ends of the cylinders being open, one of said cylinders being adapted to contain a vertically disposed motor in said cylinder, the other cylinder comprising a reservoir, a cap for the motor cylinder, a quick detachable cap for the reservoir cylinder, said first named cap having oppositely directed hand grip portions arranged centrally of the casing and intermediate said cylinders, a valve in said bore controlling discharge from said reservoir, and a coil spring in said bore and normally supporting the valve in closed position.

5. In a machine of the class described, a casing having two cylinders joined by a connecting web, said web having a bore, upper ends of the cylinders being open, one of said cylinders being adapted to contain a vertically disposed motor in said cylinder, the other cylinder comprising a reservoir, a cap for the motor cylinder, a quick detachable cap for the reservoir cylinder, said first named cap having oppositely directed hand grip portions arranged centrally of the casing and intermediate said cylinders, a valve in said bore controlling discharge from said reservoir, a coil spring in said bore and normally supporting the valve in closed position, a manually operated plunger in one of said hand grips, and an arm pivoted to said plunger and freely coupled with said valve.

6. In a machine of the character described, a casing having a pair of cylinders spaced and joined by a web, the cylinders and web having bores opening through the top thereof, one of said cylinders being adapted to contain a vertically disposed motor in said cylinder, the other cylinder forming a reservoir having a discharge port communicating with said web bore, means in the reservoir for pressure discharge of fluid therefrom, a cap closing said motor cylinder, said cap including a bore registering with the bore of said web, a plunger valve and a coil spring in the web and cap bores, said valve normally closing discharge port, means for moving the valve into open position against the action of said spring, a quick detachable cap for the reservoir cylinder, and a pair of outwardly and downwardly extending hand grips integral with the first named cap and arranged centrally of said casing.

7. In a machine of the character described, a casing having a pair of cylinders spaced and joined by a web, the cylinders and web having bores opening through the top thereof, one of

said cylinders being adapted to contain a vertically disposed motor in said cylinder, the other cylinder forming a reservoir having a discharge port communicating with said web bore, means in the reservoir for pressure discharge of fluid therefrom, a valve in the web portion, a cap closing said motor cylinder, said cap including a bore registering with the bore of said web, a quick detachable cap for the reservoir cylinder, a pair of outwardly and downwardly extending hand grips integral with the first named cap and arranged centrally of said casing, and a coil spring in the cap and web bores and engaging said valve to normally support the valve in position closing said discharge port.

8. In a machine of the character described, a casing having a pair of cylinders spaced and joined by a web, the cylinders and web having bores opening through the top thereof, one of said cylinders being adapted to contain a vertically disposed motor in said cylinder, the other cylinder forming a reservoir having a discharge port communicating with said web bore, means in the reservoir for pressure discharge of fluid therefrom, a valve in the web portion, a cap closing said motor cylinder, said cap including a bore registering with the bore of said web, a quick detachable cap for the reservoir cylinder, a pair of outwardly and downwardly extending hand grips integral with the first named cap and arranged centrally of said casing, a coil spring in the cap and web bores and engaging said valve to normally support the valve in position closing said discharge port, and manually operated means in one hand grip portion for actuating said valve.
